UNITED STATES PATENT OFFICE.

HARRY JOE GINSBERG, OF AMARILLO, TEXAS, ASSIGNOR TO STANDARD SAFETY CLAMP COMPANY, OF AMARILLO, TEXAS, A CORPORATION OF DELAWARE.

SIGN HOLDER.

Application filed April 17, 1928. Serial No. 270,771.

The present invention relates to improvements in sign holders and has reference more particularly to a holder for a placard for use upon tank cars containing inflammable liquids.

In the transportation of inflammable liquids stored in railroad tank cars, it is required by law that a placard identifying the car and its contents be displayed and upon loading a tank car with inflammable liquids it is the common practice to tack signs upon boards arranged on the car at four conspicuous places. When the car reaches its destination and the same is unloaded it is required that the placard be removed. Usually in removing the placards from their respective boards upon which the same have been tacked or nailed, the placards are torn and destroyed.

It is therefore one of the principal aims of the present invention to provide a placard holder which will enable the placard to be properly displayed for view while the tank car is in a loaded condition, the placard being readily removed and reversed in its holder after the car has been emptied.

A further object is to provide a sign holder of the above mentioned character which is of such construction as to positively secure the sign or placard in position and against being accidentally displaced from its holder, said holder embodying a spring clamp constructed in the form of a frame so that the indicating indicia on the card will not be obstructed while the card is arranged on the holder.

Still a further object is to provide a sign holder of the above mentioned character which is simple in construction, inexpensive, strong and durable and further well adapted to the purpose for which it is designed.

Other objects and advantages of the invention will become apparent from the following description when taken in connection with the accompanying drawings.

In the accompanying drawings wherein like reference characters indicate corresponding parts throughout the several views:

Figure 1 is a side elevation of the sign holder embodying my invention, showing a sign supported thereon.

Figure 2 is a vertical sectional view taken approximately on the line 2—2 of Figure 1.

Figure 3 is a view similar to Figure 2 showing the main frame in a partially open position.

Figure 4 is a detail perspective view of the main spring frame.

Figure 5 is sectional view taken approximately on the line 5—5 of Figure 1 for more clearly disclosing the J-bolt, and

Figure 6 is a view similar to Figure 1 showing a modification wherein two sign holders are employed.

In the drawings wherein for the purpose of illustration is shown the preferred embodiment of my invention, the numeral 1 designates the base of my improved sign or placard holder, the same being preferably constructed of wood.

Extending transversely through the lower portion of the rectangular shaped base 1 adjacent the respective side edges thereof are the J-bolts 2. The threaded ends of these bolts extend through the rear sides of the base and have arranged thereon the nuts 3, while the hooked ends of the bolts extend into the front side of the base, as shown very clearly in Figure 5 of the drawings.

Forming an important part of the present invention is the substantially rectangular shaped clamping frame denoted generally by the numeral 6, the same being formed from a single strand of spring wire. The sides of the rectangular frame 6 are designated by the numerals 7 and 8, respectively, while the top and bottom portions are denoted by the numerals 9 and 10, respectively, and as is clearly shown in Figure 4, one end of the wire is formed with an eye which receives the other end.

The top portion 9 of the frame 6 has its intermediate portion bent outwardly to form a finger engaging bend 11 for the purpose of actuating the main clamping frame, as will be presently described.

The base portion 10 of the rectangular frame 6 extends through the hooked ends of the bolts 2, and in this manner, the frame is capable of vertical swinging movement. A pair of axial coil springs 12 encircle the bottom portion 10 of the frame 6 adjacent the respective sides of said frame, and each spring member is so constructed as to provide a relatively short arm 13 and a relatively long arm 14 at its ends. The shorter arm of each axial coil spring is disposed laterally through a transverse opening formed therefor in the base 1 whereby the inner ends of the axial coil springs are anchored to the base as clearly indicated in Figures 2 and 3 of the drawings.

The longer outer end portions are slightly bowed and extend upwardly along the adjacent sides of the frame, the extremities of the arms being bent to form lateral hooks 15 that engage over and around the intermediate portions of the respective sides of the frame 6. The bowed portions of the arms 14 project inwardly beyond the inner faces of the arms or sides of the frame 6 for a purpose to be presently apparent, and also it is to be observed that the axial coil springs are formed of relatively fine wire so that the bowed elongated arms can be easily flexed.

These axial coil springs cooperate with the main clamping frame to normally hold the same against the front face of the base 1, and when a placard A having suitable indicia on the front face thereof is to be supported on the sign board, the frame 6 is swung outwardly away from the sign board by grasping the finger engaging portion 11, and then the placard A is placed against the front face of the base with the lower edge of the placard resting on the inwardly disposed shorter arms 13 of the axial coil springs 12. As soon as the upper portion of the frame 6 is released, the axial coil springs will swing the frame 6 inwardly toward the base. However, the bowed portions of the arms 14 will initially engage the lower portion of the placard, but will not interfere with the main clamping frame properly engaging with the placard. In this manner, the sign will be positively secured in position on the holder, and the frame will not interfere with the reading of the indicia on the sign.

The sign holder is particularly adapted to be used on tank cars containing inflammable liquid, and the placard contains suitable identification matter with reference to the tank car and the contents thereof. The sign holder is mounted in any suitable manner on the tank car, and when the car is loaded, the placard with its proper indicating matter is placed in the sign holder. When the car is unloaded, the placard is removed and reversed in the sign holder, thus obviating the necessity of having to destroy the placard and permitting the same to be used indefinitely.

The sign holder may be equally as well used in conjunction with displaying other types of signs, and it is to be understood that I do not wish to limit myself to the use of the sign holder only in connection with tank cars containing inflammable liquids.

In Figure 6 of the drawings, I have shown a modification wherein two rectangular clamping frames are provided for holding signs on a suitable base. In this instance, the base is designated by the numeral 16 and three J-bolts 17 extend through the base at spaced intervals.

An elongated strand of spring wire has one end portion 18 disposed horizontally through the hooked ends of the spaced J-bolts 17.

Said strand of wire is then bent upwardly as at 19, and thence laterally as at 20 and then downwardly as at 21 to form a rectangular frame 22, the lower end of the downwardly disposed portion being bent around the intermediate portion of the horizontal end portion 18.

An additional strand of wire is bent into substantially inverted U-shaped formation as shown at Figure 6 and the free ends of the arms of this inverted U-shaped frame 22' are bent around the horizontal portion 18 for disposition adjacent the other frame formed from the wire 18. The top portion of each of these frames 22 and 22' has its intermediate portion bent outwardly to form a finger engaging member 23 whereby said frames may be independently moved away from the base 16, axial coil springs 24 being associated with the horizontal portion 18 and cooperating with the base and the sides 19 of the frame 22 to hold said frame in position against the base. Similar axial coil springs 25 are disposed around the horizontal portion 18 for cooperation with the base and the sides of the inverted U-shaped frame 22' to maintain the latter in engagement against the base.

It will thus be seen from the foregoing description that I have provided a sign holder which can be manufactured at a very low cost, and due to its simplicity, can be readily and easily operated to facilitate the insertion or removal of a placard therefrom.

While I have shown the preferred embodiment of my invention it is to be understood that minor changes in the size, shape and arrangement of parts may be resorted to without departing from the spirit of the invention or the scope of the appended claims.

Having thus described the invention, what I claim as new and desire to secure by Letters Patent is:

1. In a sign holder of the class described, a base, a rectangular shaped clamping frame, hooked bolts extending transversely through the base, the hooked ends of the bolts receiving the base portion of the frame to provide a pivotal connection for said frame whereby said frame is capable of vertical swinging movement, a pair of axial coil springs encircling the base portion of the frame adjacent the sides thereof, the inner opposed ends of the springs being directed inwardly into the base and providing a support for the lower edge of the sign, the outer ends of the axial coil springs being directed upwardly and engaged with the respective sides of the frame for normally holding the same in clamping engagement with the sign.

2. In a sign holder of the class described, a base, a rectangular shaped clamping frame, hooked bolts extending transversely through the base, the hooked ends of the bolts receiving the base portion of the frame to provide a pivotal connection for said frame whereby

said frame is capable of vertical swinging movement, a pair of axial coil springs encircling the base portion of the frame adjacent the sides thereof, the inner opposed ends of the springs being directed inwardly into the base and providing a support for the lower edge of the sign, the outer ends of the axial coil springs being directed upwardly and engaged with the respective sides of the frame for normally holding the same in clamping engagement with the sign, said outer end portions of the axial coil springs being bowed inwardly to initially engage with the adjacent portions of the sign, the sides and top portion of the frame subsequently engaging with the sign.

3. In a sign holder of the class described, a base, a rectangular shaped clamping frame, hooked bolts extending transversely through the base, the hooked ends of the bolts receiving the base portion of the frame to provide a pivotal connection for said frame whereby said frame is capable of vertical swinging movement, a pair of axial coil springs encircling the base portion of the frame adjacent the sides thereof, the inner opposed ends of the springs being directed inwardly into the base and providing a support for the lower edge of the sign, the outer ends of the axial coil springs being directed upwardly and en-

gaged with the respective sides of the frame for normally holding the same in clamping engagement with the sign, said outer end portions of the axial coil springs being bowed inwardly to initially engage with the adjacent portions of the sign, the sides and top portion of the frame subsequently engaging with the sign, the top portion of the frame having its intermediate portion bent outward to form a finger engaging portion to facilitate outward swinging movement of the frame.

4. In a sign holder, a base, a frame pivotally secured at the bottom portion thereof on said base, and a pair of axial coil springs encircling the base portion of the frame adjacent the side thereof, the inner opposed ends of the springs being secured to the base, the outer ends of the axial coil springs being directed upwardly into embracing engagement with the respective sides of the frame normally holding the same in clamping engagement with the sign, said outer end portions of the axial coil spring being bowed inwardly to initially engage with the adjacent portions of the sign, the sides of the frame subsequently engaging with the sign.

In testimony whereof I affix my signature.

HARRY JOE GINSBERG.
